COMBINED SPRAY AND DROP DISPENSER FOR NASAL MEDICATION

Eli A. Zackheim, South Plainfield, N.J., assignor to
Johnson & Johnson, a corporation of New Jersey

Filed May 27, 1960, Ser. No. 60,752

Term of patent 14 years

(Cl. D83—1)

FIG. 1 is a side elevational view of a combined spray and drop dispenser for nasal medication embodying my new design;

FIG. 2 is a front elevational view thereof;

FIG. 3 is an elevational view taken from the side opposite that shown in FIG. 1; and

FIG. 4 is a top plan view thereof, the bottom being substantially plain.

I claim:

A combined spray and drop dispenser for nasal medication, as shown and described.
